WINDOW HEAD CONSTRUCTION OR THE LIKE

Filed March 20, 1939

FIG. 2.

UNITED STATES PATENT OFFICE

2,175,110

WINDOW HEAD CONSTRUCTION OR THE
LIKE

Hyman Cunin, Washington, D. C.

Application March 20, 1939, Serial No. 262,973

7 Claims.

(Cl. 72—59)

This invention relates in general to building constructions for window and door frames and deals, more particularly, with improved head structures therefor embodying various forms of lintels designed to prevent water leakage to the inside of the wall and otherwise adapted to direct shedded water to the outside of the wall to discharge in the area of the door or window opening.

A primary object of the invention is to provide a head structure of this character comprising a lintel having the combined purpose of a load bearing structural member spanning the top of the door or window opening to carry the super-structure, and also serving as a means directing discharge of rain or other shedded water to the area of such opening in preventing objectionable leakage of such water around the door or window frame to the inside of the wall.

Another object of the invention is for the provision of such a head structure comprising a lintel serving as a load bearing structural member and provided with substantial flanges designed to prevent shedded water from running off the ends thereof into the surrounding wall and otherwise direct such water to throw off between such flanges to be effectively discharged outwardly outside of the wall.

A still further object contemplates the provision of such a head structure employing a lintel which may be readily embodied in the usual brick or other masonry wall construction without requiring any material change therein or disturbing the customary formation in which bricks are laid in building a conventional brick wall.

Still another object is for the provision of a lintel structure of the type described comprising a plurality of simple, component parts which may be readily incorporated into a unitary structure which is strong and durable and capable of inexpensive manufacture to be available to the trade at comparatively low cost.

Further objects and advantages of the invention and other new and useful features in the construction, arrangement and general combination of the parts thereof will be readily apparent to those skilled in the art as the following description proceeds with reference to the accompanying drawings in which like reference characters designate like parts throughout the same, and in which:

Fig. 1 is a fragmentary front elevational view of a portion of a building showing the outer appearance of a window opening embodying a preferred form of the improved lintel structure of the present invention;

Fig. 2 is a sectional view taken on line 2—2 of Fig. 1, looking in the direction of the arrows;

Fig. 3 is a fragmentary perspective view of a portion of Fig. 1 showing the improved lintel as positioned spanning the window opening preparatory to the building of the super-structure thereon;

Fig. 4 is a similar fragmentary perspective view showing another form of lintel structure embodying individual flange devices;

Fig. 5 is a view similar to Fig. 3 showing a further embodiment of the invention comprising a pair of simple angle sections disposed in cooperative relation to provide a unitary lintel structural member; and,

Fig. 6 is a sectional view of a window head construction embodying the lintel structure of Fig. 5.

The several forms of lintel structures disclosed herein are shown in connection with the usual form of brick wall construction but it is to be appreciated that the same are equally adaptable to use in similar constructions employing various other forms of building materials such as reinforced concrete, stone, tiling and the like, without departing from the spirit and scope of the invention.

Referring now more particularly to Figs. 1 to 3 inclusive of the drawing, a preferred form of lintel, designated generally 10, is shown in association with a brick wall 1 having a window frame 2 mounting a window frame 3, Fig. 2, of any selected form comprising, for example, head blocks 4 and a casing 5 provided with any suitable type of molding 6, on the inner side of the wall which is usually finished off with plaster 7, 35 tiling, or the like.

As best seen in Figs. 2 and 3, a preferred form of lintel according to this invention comprises an iron or steel substantial girder of generally W-shaped cross-section and of a size and thickness 40 proportionate to the loads and strains to be imposed thereon. More specifically, the lintel is constructed in the manner of a horizontal base section 11 continuing into a vertical section 12 and an intermediate horizontal section 13 which 45 in turn continues in a top vertical section 14. On the generally W-shaped girder thus provided, substantial flanges 15, 16, are secured in suitable spaced relation, preferably at the ends thereof, as by welding 17, or any other selected fastening 50 means such as rivets, bolts, mastic or the like, capable of providing substantially water-tight connections of the flanges to the girder. Such flanges are extremely simple in construction and may be produced in various forms at very low 55

cost in the manner of inexpensive stampings from rolled iron and steel or sheet metal. Preferably such a flange is provided as a substantial plate-like element having its lower edge surface of a stepped formation corresponding to that of the girder such that it may be precisely fitted thereto to provide a close, water-tight connection by the welding or other securing means, as aforesaid.

Thus the lintel assumes the form of a unitary structural member having a generally stepped formation which may be readily embodied in substantially interlocked relation in the usual wall structure with little or no change from the customary methods of construction simply by building the wall at the top of the window opening with a substantial stepped surface, as shown in Fig. 3, corresponding substantially to the contour of the underside of the lintel. The lintel is then most effectively seated on such surface of the wall and bridging the window opening 2, as shown, whereupon the building of the superstructure to be carried thereby may be expeditiously proceeded with in completing the wall structure.

Inasmuch as the top surface of the lintel is open and of generally stepped formation, the immediately adjacent bricks or other material of the superstructure may be readily built thereon in providing the aforesaid interlocked relation of the lintel in the completed wall construction whereby it is positively and firmly held against displacement in any direction. Thus the lintel is held against inward displacement by the bricks 18, Fig. 3, comprising the inner portion of the wall at the top of the window opening in direct engagement with the rear face of vertical section 12 of the lintel. Likewise, outward shifting movement of the lintel in a completed wall construction is prevented by the bricks 19, 20, Fig. 2, carried thereby and directly engaging the upper surfaces of the vertical lintel sections 12, 14 respectively. Endwise movement of the lintel in either direction is prevented by the end flanges 15, 16, on either side of which the bricks of the superstructure are laid, as will be understood from the dotted line showing of Fig. 1 representing the position of such flanges in a completed wall construction.

A most important feature of this form of lintel structure resides in the provision of the end flanges 15, 16 of such configuration and design as to permit the same to be built into a completed wall construction without in any way disturbing the customary staggered formation in which the bricks are laid. Accordingly, as shown in Fig. 1, it will be understood that brick 21 of the wall directly overlying the flange 15, for example, is suitably clipped as indicated at 22, Fig. 2, such that the same will clear the free edge of such flange and thus be capable of being precisely embodied in the conventional staggered formation in which the bricks are laid in the completed wall construction. The outer appearance of the wall, therefore, is in no manner detracted from and since the spaces intermediate adjoining bricks are filled with mortar in accordance with well known methods of bricklaying, the lintel is entirely concealed except for the lower horizontal section 11 thereof extending over the window opening to form a dripping area from which shedded water may be readily thrown off as presently to be described.

From the foregoing, it will be understood that the improved lintel structure of this invention provides an improved head construction for a

window or door frame opening which is simple, inexpensive, easily and quickly installed, and sufficiently strong and durable to satisfy even the most stringent requirements of present day building codes. At the same time there is provided a most effective, highly practical means by which shedded water flowing down from above the window opening will be discharged outwardly outside the wall without requiring the use of any special flashing for this purpose or other special waterproofing construction, thereby providing a lintel construction of this character which overcomes all the insufficiencies of known prior constructions at the least possible cost.

The flanges 15, 16, on the lintel are suitably spaced from either side of the window opening as shown in Fig. 3 and thus provide a substantial receptacle into which water flowing from the super-structure above the door or window opening will be collected and be prevented from running off the ends of the lintel into the area of the wall surrounding the window opening where it would tend to seep through and dampen the inside of the wall. Accordingly, any water collected between such flanges 15, 16 will naturally have a tendency to flow down the stepped formation of the lintel to the lower horizontal section 11 thereof, which as shown in Fig. 2, has its free edge in the area of the window opening 2 and will, of course, discharge such shedded water outwardly outside the wall.

Fig. 4 shows a further embodiment of the invention in which a generally W-shaped lintel of the character described with reference to Figs. 1 to 3 inclusive is employed with an alternate form of flange means provided by individual substantial angle plates 30, 31, and 32, 33. These angle plates are constructed of any suitable material such as iron, steel or sheet metal material and are arranged on the lintel in a manner to dispose the respective free flanges 34, 35, and 36, 37, thereof in suitable offset relation to precisely fit in the arrangement of the bricks of the superstructure which may then be readily built up on the lintel without departing from the usual staggered formation of the bricks in the completed wall construction. Such angle plates may be rigidly secured to the lintel by any suitable means such as welding, riveting, etc. but inasmuch as the same are provided as individual elements they are preferably united to the lintel by a suitable form of mastic applied over a substantial area of the side and bottom surfaces thereof seated against the adjacent vertical and horizontal sections, respectively, of the lintel. It will accordingly be appreciated that the said flanges 34, 35 and 36, 37, serve in a manner similar to those described in the previous form of the invention, to prevent shedded water from above the window opening from running off the ends of the lintel into the surrounding wall area, and otherwise direct such water down the stepped surface of the lintel to the free edge of the lower horizontal section 11a thereof where it is readily discharged in the area of the window opening outwardly outside the wall.

Figs. 5 and 6 illustrate another form of the invention wherein the lintel structure is provided by a pair of angle sections 40, 41, arranged one upon the other in offset relation, as best seen in Fig. 6, with the horizontal portion of the upper angle section 40 overlying the adjacent vertical portion of angle section 41 to provide the generally W-shaped girder arrangement which may be readily embodied in the ordinary wall construc-

tion, substantially as set forth with respect to the form of the invention shown in Figs. 1 to 3 inclusive. This arrangement embodying a pair of separate angle sections is particularly advantageous in installations in which cost is a deciding factor since such angle sections are usually of stock dimensions and therefore may be obtained at comparatively low cost.

In a lintel structure of this character, a substantially water-tight bond therebetween can be obtained by employing a mastic or the like, between the top edge of the vertical portion of angle section 41, and the overlying horizontal portion of angle section 40. The flanges may be provided by suitable plate elements individually secured to the separate angle sections, 40, 41, by welding, riveting or the like, or otherwise provided for in the use of substantial angle plates similar to those shown and described with reference to Fig. 4, and accordingly, in a completed wall construction, such flanges 34, 35 would assume the form substantially as indicated by dotted lines in Fig. 6, showing in detail the general type of window head construction set forth in the description 25 of the form of the invention shown in Fig. 2.

An alternate construction of this form of the invention contemplates welding together the two angle sections preferably in the area in which the horizontal portion of angle section 40 overlies the vertical portion of angle section 41, thus providing a unitary structural member of the same character as the one-piece, generally W-shaped type shown in Figs. 3 and 4. The end flanges therefor may then be provided either by means of individual angle plates as shown in Fig. 35 5, or in the manner of simple, inexpensive plate-like elements similar to the flanges 15, 16, Fig. 3, and which when welded or otherwise secured to the pair of angle sections serve to reinforce and 40 strengthen the lintel structure thus provided.

While this invention has been described in detail with specific examples such examples are illustrative only, since it will be apparent to those skilled in the art that other modifications within the spirit and scope of the invention may be constructed without departing from the teaching or essential characteristics thereof. The present embodiments are therefore to be considered in all respects as illustrative and not restrictive, the 45 scope of the invention being indicated by the appended claims rather than by the foregoing description, and all changes which come within the meaning and range of equivalency of the claims are therefore intended to be embraced 50 therein.

What is claimed and desired to be secured by United States Letters Patent is:

1. In a wall construction of the class described, a combined lintel and flashing spanning a door or window frame opening provided in said wall, said lintel comprising a load bearing structural member of generally W-shaped cross-section and presenting a stepped bearing surface adapted to seat on a substantially corresponding stepped area of said wall to span said opening, said lintel supporting the super-structure of said wall built up thereon over the window opening and being substantially interlocked in the completed wall construction, and flanges on said lintel adapted to prevent shedded water from above the window opening from running off the ends thereof into the area of the wall adjacent said window opening.

2. In a wall construction of the class described, 75 a combined lintel and flashing spanning a door

or window frame opening provided in said wall, said lintel comprising a load bearing structural member of generally W-shaped cross-section and presenting a stepped bearing surface adapted to seat on a substantially corresponding stepped area of said wall to span said opening, said lintel supporting the super-structure of said wall built up thereon over the window opening and being substantially interlocked in the completed wall construction, and flanges spaced apart on said lintel on either side of the window opening for preventing shedded water from above the window opening from running off the ends thereof into the surrounding area of the wall and to direct such water to the area of the window opening to discharge outwardly outside the wall.

3. In a wall construction of the class described, a combined lintel and flashing spanning a door or window frame opening provided in said wall, said lintel comprising a load bearing structural member of general W-shaped cross-section and presenting a stepped bearing surface adapted to seat on a substantially corresponding stepped area of said wall to span said opening, said lintel supporting the super-structure of said wall built up thereon over the window opening and being substantially interlocked in the completed wall construction, and flanges on said lintel adapted to prevent shedded water from above the window opening from running off the ends thereof into the adjacent area of the wall, said flanges being arranged in offset relation to direct such shedded water down the stepped surface of the lintel to discharge in the area of said window opening outside said wall.

4. In a brick wall construction of the class described, a combined lintel and flashing spanning a door or window frame opening provided in said wall, said lintel comprising a load bearing structural member of generally W-shaped cross-section and presenting a stepped bearing surface adapted to seat on a substantially corresponding stepped area formed by the bricks of said wall to span said opening, said lintel supporting the super-structure of said wall built up thereon over the window opening and being substantially interlocked in the completed wall construction, and flanges on said lintel adapted to prevent shedded water from above the window opening from running off the ends thereof into surrounding area of the wall, said flanges being arranged to direct such shedded water down the stepped surface of the lintel to discharge in the area of said window opening outside said wall, those bricks of the wall directly overlying the flanges being formed to clear the extremities thereof in preserving the general staggered formation in which the bricks are laid in the completed wall construction.

5. In a wall construction of the class described, 60 a combined lintel and flashing spanning a door or window frame opening provided in said wall, said lintel comprising a load bearing structural member of generally W-shaped cross-section and presenting a stepped bearing surface adapted to seat on a substantially corresponding stepped area of said wall and bridge said opening, said lintel being provided with spaced apart flanges and supporting the super-structure of said wall built up thereon over the window opening, said flanges being provided by substantial angle plates secured to the lintel in offset relation, said lintel being substantially interlocked in the completed wall construction and said flanges being adapted to direct shedded water from the super-structure 65 70 75

to the area of the window opening to discharge outwardly outside said wall.

6. In a wall construction of the class described, a combined lintel and flashing spanning a door or window frame opening provided in said wall, said lintel comprising a pair of angle sections disposed one upon the other in offset relation to provide a load bearing structural member of generally W-shaped cross-section, said lintel supporting the super-structure of said wall built up thereon over the window opening and being provided with spaced apart flanges adapted to direct shedded water from the super-structure to the area of the window opening to discharge outwardly outside said wall.

7. In a wall construction of the class described, a combined lintel and flashing spanning a door or window frame opening provided in said wall, said lintel comprising a pair of angle sections disposed one upon the other in offset relation to provide a load bearing structural member of generally W-shaped cross-section, said lintel supporting the super-structure of said wall built up thereon over the window opening, spaced flanges on said lintel provided by substantial angle plates, said flanges being adapted to direct shedded water from the super-structure to the area of the window opening to discharge outwardly outside said wall.

HYMAN CUNIN.
